AIR CIRCULATION CONTROL SYSTEM

William A. Ray, Los Angeles, Calif., assignor to
General Controls Co., a corporation

Application August 19, 1944, Serial No. 550,160

3 Claims. (Cl. 98—1)

1

My present invention relates to temperature control systems for houses or other structures, and more particularly to systems wherein circulation of a fluid medium, such as outdoor air, which periodically varies in temperature above and below the temperature of the structure is employed for changing the temperature thereof in a desired sense. An example of such a system is found in the "attic cooler" commonly in use in regions where the temperature of the outdoor air becomes considerably lower than that of the house during the night. The "attic cooler" comprises means, such as a fan installed in the attic, for withdrawing the warm air from the house and replacing it with cool air from outdoors. The circulation of air is manually started during the evening; time-controlled means usually being provided for stopping the circulation at a predetermined time of the morning. This method of control is not very effective for the reason that the circulation is stopped regardless of prevailing climatic conditions which might make it advantageous to set the time of stopping ahead, or even behind. Thermostatic control of the circulation by means responsive to the temperature of the outdoor air or of the house is also not fully effective since no consideration is then given to the fact that at the particular temperature at which the circulation is stopped there may still be a favorable difference between the indoor and outdoor temperatures. It is therefore an object of this invention to provide, in connection with a system of the general character described above, means for stopping circulation of the medium when its temperature and that of the space influenced thereby become substantially equal.

Another object of the invention is to provide means for stopping the circulation when the temperature of the space starts to change in a sense opposite to that desired.

Another object is to provide means responsive to the difference between the temperature of the medium and that of the space for stopping the circulation when said difference becomes substantially zero.

Other objects and advantages of the invention will be found in the description, the drawing, and the claims; and, for full understanding of the invention, reference is to be had to the following detailed description and accompanying drawing, wherein:

Figure 1 is a front elevation of a control device embodying my invention;

Figure 2 is an enlarged fragmentary section taken along the line 2—2 of Fig. 1; and

2

Figure 3 is a front elevation of a modified form of control device according to the invention.

Referring first to Figs. 1 and 2 of the drawing, the numeral 11 indicates a base upon which a bracket 12 is pivotally mounted at 13. Secured by a strap 14 to the bracket is a mercury switch comprising a glass tube having, fused therein, contact elements 16 and containing a globule of mercury 17 adapted to bridge the elements when the bracket is tilted counterclockwise, as shown. Indicated at 18 is a pair of electric service lines which are connected, in series with the mercury switch, to an electric fan 19.

Mounted on the lower part of the base 11 is a temperature responsive device comprising a sealed expandible-contractible metallic bellows 20 containing a thermally expansive fluid. The left-hand end of the bellows is rigidly secured to the base by a strap 21 and its movable right-hand end or head is provided with an extension 22 engageable with an abutment 23 extending from the front surface of a gear 24 pivotally mounted on the base. The gear 24 meshes with another gear 25 mounted on a pin 26 extending from the base, this pin also supporting a catch arm 27. As is seen in Fig. 2, catch arm 27 and gear 25 are held together, and against a shoulder formed by an enlarged portion 28 of the pin, by a spring washer 29; a friction disk 30, of cork or the like, being interposed between the catch arm and the gear. The catch 27 has a free fit on the pin; gear 25 preferably fitting tightly, and the pin 26 being freely rotatable on the base. Connected at its opposite ends to gear 25 and to the base is a spiral spring 30 which urges the gear in a counterclockwise direction, as viewed in Fig. 1, so that the abutment 23 of gear 24 follows the movement of projection 22 of bellows 20 when the same contracts.

Catch arm 27 cooperates with the corner portion 31 of the switch bracket 12, this corner being shown in Fig. 1 as resting on a shoulder 32 formed on the catch arm adjacent its top. The bracket 12, together with the mercury switch, is biased by gravity in a clockwise direction so that if the catch arm is rotated out of engagement with the bracket the same is tripped into engagement with a stop pin 33; the switch then being so tilted that the mercury flows out of contact with the elements 16.

In connection with the operation of the control device described above, it will be assumed that the fan 19 is arranged to circulate outdoor air to the interior of a house and that the temperature responsive device, comprising bellows 20, is with-

in the house (preferably close to some incoming air stream) and responds to the temperature thereof. With the parts in the positions shown in Fig. 1 the system is in operation, as during the night. As the temperature of the house falls due to the circulation of air, the bellows 20 contracts, with the result that gears 24 and 25 rotate under the force of spring 30 as the abutment 23 follows the movement of the bellows. In this rotation of the gears, the catch arm 27 slips with respect to gear 25 since it is restrained from counterclockwise rotation by the engagement with its shoulder 32 of the corner 31 of the switch bracket. When, normally in the early morning, the temperature of the outdoor air rises to a degree at which it is no longer effective to cool the house (or rises above that of the house), the bellows 20 starts to expand due to rise of house temperature. When this occurs, the gears 24 and 25 are rotated in directions to disengage the catch arm 27 from the switch bracket 12; there being no appreciable impedance to the movement (by its frictional engagement with gear 25) of the catch arm in that direction. When the catch has moved through a distance corresponding to the width of its shoulder 32, the switch bracket trips by gravity (into engagement with stop 33) to effect deenergization of the fan and stoppage of the circulation of air—the cooling system remaining inoperative until the switching means is "manually reset," as will be described. As the temperature of the house continues to rise during the day, the catch 27 rotates clockwise until its movement is arrested by engagement of its lower portion with the extension 34 of the switch bracket.

To reinitiate operation of the system, the handle 35 of the switch bracket is raised; the bracket extension 34 moving catch arm 27 until its tip 36 is engaged by the corner 31 of the bracket, the catch arm then being in vertical position so that when the bracket is released it rests in the position shown in Fig. 1.

Referring now to the modified form of control device shown in Fig. 3, the numeral 41 indicates a base whereon is mounted a bracket 42, rockable about a pivot 43, which carries a mercury switch comprising a tube 44 having the usual contact elements 45 and globule of mercury 46. The switch is connected to control supply of energy to an electric fan 47 from service lines 48. Mounted on the lower part of the base is a pair of expandable-contractible bellows 49 and 50, the outer ends of which are rigidly secured to the base by straps 51 and 52; the adjacent movable inner ends or heads of the bellows being attached to opposite ends of a connecting member 53. Bellows 49 is fluidly connected by a capillary tube 54 to a thermal bulb 55, the bellows 50 by tube 56 to another bulb 57. For adjustably biasing the bellows system in either direction there is provided a resilient member 58, the upper end of which is disposed between a pair of pins 59 extending from the connecting member 53. The direction and degree of tension of the resilient member is controlled by rotation of a knob 60 by means of which the lower portion of this member is secured to the base. The bellows 49 and 50 and their associated thermal bulbs 55 and 57 are charged with a thermally expansive fluid which is also compressible or elastic so that no destructive force is set up by simultaneous expansion or contraction of both bellows resulting from like temperature changes at the bulbs. Rotatably mounted on a pin 61 extending from

the base is a catch arm 62, the upper end of which is formed to provide a shoulder 63 upon which the lower corner 64 of switch bracket 42 rests when the switch is in circuit-closing position, as shown. Between the lower end of the catch arm and an extension 65 of the bellows-connecting member 53 is a lost-motion or flexible connection 66 which may be a piece of cord or fine wire.

The operation of the control apparatus of Fig. 3 will be described in connection with the same type of house-cooling system as was described above in connection with Figs. 1 and 2; it being assumed that bulb 55 is arranged to respond to the temperature of the house, and bulb 57 to that of the outside air. The parts are shown in Fig. 3 in the positions in which they are when the cooling system is in operation and the temperature of the outdoor air is slightly lower than that of the house. If such difference of temperature increases during the night, the extension 65 moves in a right-hand direction so that the catch-arm connection 66 slackens. When, normally toward morning, the temperature of the house approaches that outdoors, the parts will again be in the positions shown in the drawing. As the indoor and outdoor temperatures become substantially the same, the extension 65 moves far enough toward the left to effect, through the then tightened connection 66, disengagement from its shoulder 63 of the switch bracket 42; the bracket tilting by gravity into engagement with a stop 67 to effect deenergization of the fan.

The control device of Fig. 3 is usually arranged to effect stoppage of the circulation when the temperature of the outdoor air is still slightly below that of the house; however, under some circumstances it may be desirable to continue circulation of air even when its temperature is somewhat above that indoors, as, for example, to provide ventilation while cooking is in progress. Either of these conditions of control can be met by adjustment of the bias applied to the bellows system by member 58.

To reinitiate night operation of the system, the handle 68 of the switch bracket is raised so that catch arm 62 is tilted clockwise; this arm being biased by gravity to vertical position so that (when temperature conditions are such that the connection 66 is slack) the shoulder 63 of the arm is in position to receive the corner 64 of the switch bracket when the handle is released.

In the systems described above it is assumed that circulation of the air is controlled by starting and stopping an electric fan; however, it is obvious that similar results could be achieved by opening and closing dampers or the like if other means for circulating the air are available.

The system of this invention has utility in connection with control of circulation of any fluid which normally has a beneficial temperature relation to the space with respect to which it is circulated, but which at times may vary in temperature in an undesired sense—as, for example, in a system wherein a liquid is employed for heating a space, circulation of which should be stopped in the event that for some reason the liquid becomes cool.

The embodiments of my invention herein shown and described are obviously susceptible of modification without departing from the spirit of the invention, and I intend therefore to be limited only by the scope of the appended claims.

I claim as my invention:

1. In a system for cooling a house by circula-

tion of outdoor air to the interior of the house: means for effecting said circulation of air, electrically-operable means for operating said circulation-effecting means, switching means for controlling said electrically-operable means and biased to circulation-stopping position, means manually movable to a position to set said switching means in circulation-starting position, means responsive to the temperature of the house for so operating said movable means as to trip the switching means to circulation-stopping position upon rise of house temperature, and means for maintaining said temperature responsive means continuously in operative relation to said movable means so that the switching means is tripped upon any rise of house temperature, said maintaining means including means forming a slip-clutch.

2. In a system for cooling a house by circulation of outdoor air to the interior of the house: means for effecting said circulation of air; electrically-operable means for operating said circulation-effecting means; a switch for controlling said electrically-operable means; stop means, manually settable to active position, for temporarily maintaining said switch in circulation-effecting position against the force of said bias, said stop means being movable in one direction to trip said switch to its biased position; means movable in response to variations of the temperature of the house; means frictionally connecting said temperature-responsive means to said stop means; said temperature-responsive means being capable, upon any rise of temperature of the house, of effecting through said friction connection movement of said stop means in said one direction to trip said switch; and means for preventing movement of said stop means in an opposite direction while it is maintaining said switch in circulation-effecting position, said friction connection then serving as a slip-clutch.

3. In a system for cooling a house by circulation

of outdoor air to the interior of the house: an electric fan for effecting said circulation; a switch for controlling the operation of said fan; stop means, manually settable to active position, for temporarily maintaining said switch in closed position against the force of said bias, said stop means being movable in one direction to trip said switch to open position; means movable in response to variations of the temperature of the house; means forming a clutch frictionally connecting said temperature-responsive means to said stop means; said temperature-responsive means being capable, upon any rise of house-temperature, of effecting through said clutch movement of said stop means in said one direction to trip said switch; and means for preventing movement of said stop means in an opposite direction while it is maintaining said switch in closed position, said clutch then serving to permit movement of said temperature-responsive means relative to the stop means with fall of temperature.
